UNITED STATES PATENT OFFICE.

JOHN A. HOLMQUIST, OF WOODLAWN, PENNSYLVANIA.

REEL.

1,375,844.

Specification of Letters Patent. Patented Apr. 26, 1921.

Application filed May 29, 1920. Serial No. 385,133.

To all whom it may concern:

Be it known that I, JOHN A. HOLMQUIST, residing at Woodlawn, in the county of Beaver and State of Pennsylvania, a citizen 5 of the United States, have invented or discovered certain new and useful Improvements in Reels, of which improvements the following is a specification.

My invention relates to improvements in 10 reels. In the production for the market of such material as wire, and notably barbed wire for fencing, there is need for a reel which shall be strong, simple, inexpensive, of relatively little weight, and capable of 15 being introduced into the machine where its burden is coiled upon it. It is advantageous also that such a reel be collapsible, that it may be stored in quantity in minimum space. It is such a reel which constitutes my present 20 invention.

In the accompanying drawings Figure I shows the reel in perspective, in position to receive its burden; Fig. II shows in side elevation the same reel when collapsed; Fig. 25 III is a view similar to Fig. I but fragmentary, showing a modification in structural detail.

The reel of my invention is made of wire and is composed of four pieces, two pairs of 30 duplicate parts, properly articulated together.

Each of these parts is formed of a single 35 length of wire, its ends joined (preferably by welding) to form a loop and brought to the particular shape shown.

Two of these four loops of wire are shaped 40 as the drawings show, to the form of an elongate rectangular loop with its terminal portions 2 deflected into planes at right angles to the plane of the medial portion 1. The medial portion consists of two parallel reaches; the terminal portions are bends of wire connecting the two reaches which constitute the medial portion.

45 The other two of the four loops extend, each in substantially a single plane, and may be defined as elongate rectangular loops whose opposite and otherwise parallel sides are bent midway of their length to overlapping 50 bends 3, leaving the ends 4 similar to the terminal portions 2 of the parts first described.

These parts are properly proportioned one to another and are articulated as best 55 shown in Fig. I; the two loops first described

are arranged back to back, that is to say, with their angular end portions 2 extending oppositely away from one another, and this pair of loops is hinged together by the second pair of loops. The corners *a* of the loops 60 first named engage the side reaches of the second pair of loops, at points adjacent and at opposite sides of the bends 3. The corners *a* are after assembling preferably shaped about the wire introduced into the corner, 65 to the end that while the joint remains a hinged joint, the parts will not in service separate.

The structure will be clearly understood from Fig. I, and the manifest collapsibility 70 is illustrated in Fig. II.

The modification shown in Fig. III consists merely in this, that the hinge joint at corners *a* is made by a complete turn of one strand of wire around the other. This is 75 effected by intruding the bend 2 of one of the pairs of loops between the bends 3 of one of the other pairs before the corner twists are completed, and then completing the twists.

When assembled the four reaches 1, spaced 80 apart at the corners of an approximate square (in cross-sectional plane), constitute the core of the reel; while the bends 2, 2 and 4, 4, coming into common planes, constitute the end flanges. The overlapping bends 3 85 form eyes, and these eyes at opposite ends of the reel, being alined, afford bearing for an arbor of such sort as the user may find convenient to introduce.

I claim as my invention:

1. A reel composed of four endless lengths 90 of wire, two bent into three planes, two extending each in a single plane, the two members last named articulated to the two first named at the bends thereof.

2. A reel composed of four endless lengths 95 of wire, two bent each into three planes and consisting of a medial portion of parallel reaches and opposite terminal portions parallel one to another and perpendicular to the medial portion and consisting of bends connecting the medial reaches, the other two endless lengths being bent to the form of elongate rectangles with overlapping bends intermediate their long sides, the two members last named articulating together the two members first named, substantially as described.

3. A reel composed of wire; its core portion formed of four strands of wire in quad- 110

rangular relative positions, and each end flange of the reel composed of four wings; two opposite wings of each end flange being formed of a single length of wire and the 5 other two opposite wings being formed of wire in continuous length with the wires of the core portion, substantially as described.

In testimony whereof I have hereunto set my hand.

JOHN A. HOLMQUIST.
